ATTORNEY

UNITED STATES PATENT OFFICE.

JAMES MYERS, OF BOWELL, ALBERTA, CANADA.

MACHINE FOR DRESSING CONTACT SURFACES OF COMMUTATORS.

Application filed December 28, 1921. Serial No. 525,522.

To all whom it may concern:

Be it known that I, JAMES MYERS, a citizen of the Dominion of Canada, residing at Bowell, in the county of Medicine Hat 5 and Province of Alberta, Dominion of Canada, have invented certain new and useful Improvements in Machines for Dressing Contact Surfaces of Commutators, of which the following is a specification.

10 The present invention appertains to a new and useful device for re-grinding or dressing worn or uneven contact surfaces of commutators which are adapted for use more particularly on the so called Ford 15 or Fordson motors.

The principal object of the invention is to provide a device of the character described which is capable of performing the aforementioned operation accurately and 20 thoroughly, requiring no especial skill to operate the device and in the minimum length of time.

Among the other aims and objects of the invention may be cited the provision of a 25 device of the character described with a view to compactness, in which the number of parts is few, which may be economically constructed and is symmetrical in appearance.

30 With these and other objects in view, the invention consists in the construction, combination and arrangement of parts as will be hereinafter fully described, illustrated in the accompanying drawings and pointed out in 35 the claims hereunto appended.

In the drawings:

Figure 1 is an end elevation of the device.

Figure 2 is a side elevation.

Figure 3 is a top plan view.

40 Figure 4 is a transverse section taken on line 4—4 of Figure 3.

Figure 5 is a vertical longitudinal section illustrating portions in elevation.

Figure 6 is a perspective view of the base, 45 and

Figure 7 is a perspective view illustrating the gear holding bracket.

Figure 8 is an end elevation.

In the drawings similar characters of reference designate like parts.

The numeral 9 indicates the base of the device which has lugs 10, 11, 12 and 13 integral therewith and extending laterally. 55 Apertures 14, 15, 16 and 17 are bored in these lugs for reception of bolts, the func-

tion of which is to secure the base to a suitable support. A web 18 integral with the arcuately configurated portions of the base and extending vertically therefrom has the bearings 19 and 20 formed on its upper 60 extremity, the function of which will be later explained.

Referring now more particularly to Figures 4 and 5 a sleeve 21 is positioned in a longitudinal aperture in the base 9. An 65 arm 22 is integral with the sleeve 21 and diverges into a semi-circular bracket indicated by the numeral 23, more clearly illustrated in Figure 7. The semi-circular member 24 clamps to the semi-circularly 70 configurated member 23 by means of bolts 25 passing through lugs 26 and 27 and the lugs 28 and 29 of each respective member. 30 indicates a gear which has an open central portion and an annular race indicated 75 by the numeral 31 integral therewith and extending inwardly. In this race are seated the members 23 and 24. It may be necessary to shim the member 24 to permit free rotation of the member 30, although the 80 embodiment of the shims has not been illustrated.

Transverse shaft 32 is rotatably positioned in the longitudinal aperture in the sleeve 21 and if desired the interior of the 85 sleeve may be babbitted, forming a proper bearing. A pinion 33 is secured to the outer terminal of the shaft 32, the function of which will be explained later. A collar 34 positioned on the sleeve 21 secures the 90 same in position. Pulley 35 is positioned on one terminal of the shaft 32 and has an offset hub 36. The numeral 37 indicates a set screw which secures the pulley wheel 35 to the shaft 32. Bearings 19 and 20 are 95 provided with caps 38 and 39 secured in position by means of the bolts 40. Journalled in the bearings 19 and 20 is the shaft 41 on which is keyed or otherwise substantially secured the pulley 42. On the inner 100 terminal of the shaft 41 a washer 43 is positioned. A fibre washer 44 bears against the washer 43. The emery wheel 45 bears against the fibre washer 44, the function of which is to secure the same rigidly without 105 breaking. The emery wheel 45 is secured in position by means of the washer 46 and the nut 47 which is mounted on the threaded terminal 48 of the shaft. On the opposite extremity of the shaft a pulley 49 is posi- 110

tioned. Washer 50 is positioned intermediate the pulley 49 and the emery wheel 51. Washer 52 bears against the outer face of the emery wheel 51 and in co-operation 5 with the sleeve 53 and the nut 54, which is positioned on the threaded terminal 55 of the shaft, secures the emery wheel 51 in position.

It is obvious that the hub 36 being offset 10 from the pulley wheel 35 permits the same to assume vertical alignment with the pulley 49. Belt 56 is trained over the pulley wheel 35 and the pulley 49, the function of which is to transmit power from the 15 shaft 41 to the shaft 32.

Referring more particularly to Figures 3 and 4 a lug 57 integral with the semi-circular member 23 more clearly illustrated in Figure 7 has a bolt 58 passing through the 20 same. The opposite terminal of this bolt passes through an aperture 59 in the web 18 of the base and has a head 60 positioned on the web 18. A washer 61 and collar 62 are illustrated, although the same are not essential. Coil spring 63 is positioned over the bolt 58 intermediate the collar 62 and the lug 57. Wing nut 64 is positioned on the outer threaded terminal 65 of the bolt 58. When the wing nut 64 is turned the same 30 bears against the lug 57 moving the gear 30 laterally, the object of which will be explained later.

A member 66 is secured in position by means of the bolt 68. One terminal 69 of 35 the member 66 bears against the extended portion 70. The opposite terminal of this member is enlarged as indicated by the numeral 71 and has a threaded aperture in which is positioned the member 72. The 40 commutator, the contact surface of which is to be re-ground, is indicated by the numeral 73 and is clearly shown in position in Figure 5. The inner edge of the commutator seats in the recessed portion 74. When the commutator is in position as indicated in Figure 5, the member 66 is positioned as illustrated. The terminal 69 of the member 66 bears against the extended portion 70 integral with gear 30. The member 72 is positioned 45 in the opposite terminal of the member 66 and is then actuated until the inner terminal thereof bears against the concave portion 75 of the commutator and secures the same rigidly in position, the grinding operation then takes place.

Power is applied to the pulley 42 from any suitable source, such as an electric motor, and is transmitted from the shaft 41 to the shaft 32 by means of the belt 56 trained 50 over the pulley 49 and pulley wheel 35. The pinion 33 mounted on the opposite terminal of the shaft 32 drives the gear 30 in the opposite direction to that of the emery wheels 45 and 51. It is obvious that with 55 the ratio of gearing as described and illus-

trated, the emery wheel 45 will rotate at a much greater speed than the gear 30. The emery wheel 45 bears against the inner contact surface of the commutator and grinds the worn and uneven surface of the same 70 true. The amount to be ground may be regulated by means of the wing nut 64, which upon actuation, moves the gear 30 and its associated mechanism and commutator laterally towards or away from the 75 emery wheel 45. The gear 30 rotated in the opposite direction to the high speed emery wheel 45 effects an evenly ground contact surface in the commutator.

When the commutator is ground the actuation of the shaft 41 is stopped and the member 72 rotated retrogressively. This permits the member 66 to be turned laterally, thus permitting the removal of the commutator. The emery wheel indicated by 85 the numeral 51 is to be used for sharpening tools or for any other useful purpose.

From the foregoing description it will be readily apparent that I have provided a device of the character described which is 90 capable of performing the alleged functions efficiently and economically and while this specification manifests in detail the present and preferred construction of the invention, I desire to have it understood that such deviations from such detail may be resorted to as do not form a departure from the spirit 95 of the invention as defined by the appended claims.

What I claim as new is:

1. A device of the character described, comprising in combination a base, a sleeve positioned in the said base having a supporting bracket integral with one terminal thereof and extending upwardly, a driven shaft through the said sleeve, a pinion on the said driven shaft to drive a gear and commutator holding mechanism rotatably mounted on the said supporting bracket, gear and commutator holding mechanism, a drive shaft journalled on the said base, grinding mechanism on the said drive shaft, means actuating the said driven shaft by the said drive shaft and means imparting lateral movement to the said gear and commutator holding mechanism for the purpose set forth.

2. A device of the character described, comprising in combination a base, a sleeve in the said base having a supporting arm integral with one terminal thereof, the said supporting arm formed into a semi-circular member, a semi-circular member engageable with the said semi-circular member, a driven shaft through the said sleeve, a pinion on the said driven shaft to drive a gear and commutator holding mechanism rotatably mounted in the said semi-circular members, gear and commutator holding mechanism, a drive shaft journalled on the said 120

base, grinding mechanism on the said drive shaft, a pulley on the said drive shaft, a secondary pulley on the said drive shaft, a pulley wheel on the said driven shaft, a belt 5 trained over the last mentioned pulley and said pulley wheel and means imparting lateral movement to the said commutator holding mechanism for the purpose set forth.

3. A device of the character described, 10 comprising in combination a base, a sleeve in the said base having a supporting arm integral with one terminal thereof, the said supporting arm formed into a semi-circular member, a semi-circular member, engageable 15 with the said semi-circular member, a driven shaft through the said sleeve, a pinion on the said driven shaft to drive a gear and commutator holding mechanism rotatably mounted in the said semi-circular members, 20 gear and commutator holding mechanism, a drive shaft journalled in the said base, grinding mechanism on the said drive shaft, a pulley on the said drive shaft, a secondary pulley on the said drive shaft, a pulley 25 wheel on the said driven shaft, a belt trained over the last mentioned pulley and said pulley wheel and means imparting lateral movement to the said commutator holding mechanism for the purpose set forth, said 30 means comprising a member extending from the said base through a lug on the said gear, a portion of the said member extending through the said lug and threaded for the reception of a wing nut, a coil spring over the said member intermediate the said lug and the said base, substantially as described.

4. A device of the character described, 35 comprising in combination a base, a sleeve in the said base, having a supporting bracket integral with one terminal thereof and extending upwardly, a driven shaft through the said sleeve, a pinion on the said driven shaft to drive a gear and commutator holding mechanism, gear and commutator holding mechanism, the said commutator holding mechanism consisting of an annular recessed portion, a flange centrally disposed in the said gear and offset therefrom, a post on the said gear, an arm pivoted intermediate its ends on the said post, one terminal 40 of the said arm arranged to bear against a projection on the said gear, a member threadedly engaged with the opposite terminal of the said arm, the inner terminal of the said member arranged to bear against the commutator to be secured, a drive shaft journalled on the said base, grinding mechanism on the said drive shaft, means actuating the said driven shaft by the said drive shaft and means imparting lateral movement to the said gear and commutator holding mechanism for the purpose set forth.

In testimony whereof, I hereunto affix my signature in the presence of two witnesses.

JAMES MYERS.
